UNITED STATES PATENT OFFICE.

GEORGE TRUBEL, OF MACOMB, ILLINOIS.

OIL-CAN.

SPECIFICATION forming part of Letters Patent No. 349,768, dated September 28, 1886.

Application filed February 4, 1886. Serial No. 190,782. (No model.)

To all whom it may concern:

Be it known that I, GEORGE TRUBEL, a citizen of the United States, residing at Macomb, in the county of McDonough and State of Illinois, have invented certain new and useful improvements in Oil-Cans; and I do hereby declare the following to be a full, clear, and exact description of the invention, such as will enable others skilled in the art to which it applies to make and use the same.

In the accompanying drawings, Figure 1 is a vertical central longitudinal section of my improved oil-can in the line *yy* of Fig. 5. Fig. 2 is an enlarged detail sectional view of that portion of the can which is provided with a shoulder which supports the weight of the can and oil contained therein. Fig. 3 is an enlarged detail sectional view of a lower or bottom portion of the can represented in Fig. 1. Fig. 4 is a plan view of the metal top or cover of the can shown in Fig. 1, but detached and inverted in order to clearly show the relative position of its filling-nozzle, pouring-spout, and air and drip holes, as well as the air and drip spout. Fig. 5 is a transverse section in the line *xx* of Fig. 1; and Fig. 6 is a detail broken view, in elevation, of a portion of the body of the can and of the shoulder-band of its surrounding jacket, to which the ear of the can handle or bail is applied.

My invention consists in the construction, arrangement, and combination of parts of an oil-can, as will be hereinafter described and specifically claimed, whereby an oil-can is produced adapted for containing kerosene and other oils which is not only of attractive appearance, but which, with other advantages, will catch the drippings which usually flow down the outside of an oil-can spout after pouring oil out from the can, as well as the drippings which are apt to flow down between the body of a can and its inclosing-jacket, as ordinarily constructed.

A indicates the body of my improved oil-can, made of glass, which may be in form of a hollow cylinder having its upper end contracted to an approximately-conical form and terminated with a filling-neck, as *a*, and supplied with a double tin cover, *B*, cemented to its neck *a*. This cover is made with an upper metal plate, *b*, having an annular portion,

b', turned down, as shown, so as to surround the neck *a*, and between which portion *b'* and the neck the cement is placed to secure the cover in position upon the can.

55

Encircled by the plate *b*, and beneath the same, as shown, I apply a metal disk, *b'*, having its perimeter turned up, as at *c*, and snugly fitting against the upper inner surface of the portion *b'*, thus leaving an air space or chamber, as *d*, between the plate *b* and disk *b'*.

F is the filling-nozzle of the can, having a removable screw-cap, *f*, thereon. The base of this nozzle is inserted through a proper aperture in the plate *b*, and fits over an annular turned-up lip, as *c'*, which bounds an aperture through the disk *b'*, communicating with the bore of the nozzle *F*, as shown, while to the annular lip *c* and the plate *b* said nozzle is securely soldered in position, as indicated in Figs. 1 and 4.

E is the pouring-spout of the can, and is made to communicate with its interior through the plate *b* and disk *b'*, while *E'* is a drip-spout, which is made to communicate, as shown, with the chamber *d*, which in turn communicates with the interior of the can through openings *g g*, which are located nearly in rear of the filling-nozzle *F*, and near the rear portion of the neck *a*. Such location or arrangement of the openings *g g* is made in order that when the can is tipped forward to discharge oil from the spout *E* the flowing-level of the oil will always be forward of and below said openings *g*, and thus will discharge properly through the spout *E*, instead of flowing into the chamber *d* through the openings *g*, and thence out through the drip-spout *E'*, and so becoming wasted. This drip-spout has its discharge end *e* a short distance below the discharge end *e'* of the spout *E*, and thus after oil has been poured from the spout *E* the drip from its end *e'* will run along down the under side of *E* and enter the drip-spout *E'*, through its discharge end *e*, and so

pass on into the chamber *d*, and thence into the interior of the can through said openings *g g*. Thus constructed, the chamber *d* subserves a double purpose, in that it receives and conducts the "drip" from the pouring-spout *E* into the interior of the can through openings *g g*, and also serves as an airway to conduct air entering it through the drip-spout *E'* into the body

of the can through the openings *g g* when oil is poured from the can through the pouring-spout *E*.

As shown clearly in Figs. 1 and 2, the body 5 *A* of the can at its upper portion is constructed with a projection or shoulder, *h*, which extends entirely around said body and serves, in conjunction with a jacket, as presently described, to support the weight of the can and its contents at all times free from contact with the floor upon which the can may be placed. This jacket is composed at its top of a shoulder-band, *H*, of lapped or double thickness of tin, upon which the shoulder *h* rests, and at its 15 bottom with a base-band, *H'*, of like lapped metal and thickness, as shown, said bands being connected by vertical longitudinal metal supports *m m' m² m³*, which metal supports have their top ends soldered between the two 20 thicknesses or laps of the shoulder-band *H*, and their bottom ends between the two thicknesses or laps of metal composing the base-band *H'*, and thus are held firmly in place.

So far I have only described the skeleton of 25 the "jacket" which I have made to inclose the can, and to complete the jacket I inclose the body *A* between the bands *H* and *H'* with two pieces of pasteboard, as *N N'*, the upper and lower ends of said pieces being confined, respectively, between the laps of the shoulder-band *H* and base-band *H'*, as shown, while their longitudinal edges are respectively confined between the laps of the respective longitudinal supports *m' m²* and *m m³*, as signified 30 in Fig. 5, thus leaving on opposite sides of the glass body *A* uncovered spaces, as *r r'*, extending nearly from top to bottom of the can, through which the oil in the glass can-body *A* may be observed, and so determine when it is necessary to have the can replenished. Practically the shoulder *h*, upon which the weight of the can and contents falls, may extend out only flush with the outer surface of the shoulder-band *H*, though I have shown it somewhat 35 projecting beyond said band, the shoulder being rounded in order that any oil which might overrun the can in filling will be prevented from flowing down between the jacket and the can, and made to flow down upon the exterior 40 of the band *H*, and thence upon the pasteboard covering *N N'*, from which it can be readily wiped, and thus keep the exterior of the can clean and tidy, whereas those oil-cans in use 45 which are clothed with a jacket, but have no shoulder *h*, allow the body of the can to slip down in the jacket, and thus a casual overflow of oil in filling will run down between the jacket and the can, and so drip from the can for days after it has been filled. Thus the shoulder *h* 50 subserves two functions, the main one being to sustain the weight of the can and contents, and the other to prevent overflow oil from running down between the jacket and the can. If, however, any oil should happen to find its 55 way between the band *H* and pasteboards *N N'* and the body portion *A*, and so run on down

to the bottom *s*, such drip will there be caught and absorbed by a soft paper disk, *T*, which I insert in contact with said bottom and within the band *H'*, as shown, thus effectually preventing any oil coming in contact with a table or floor or support on which the can may be set, thus avoiding one of the most disagreeable results of the use of an oil-can. The absorbent paper disk *T* is held in place by punching with 70 a proper tool burrs, as *v*, in the band *H'*, the burrs being made to engage with the disk *T*, as shown, and so hold it in place. This disk is not made to extend down flush with the bottom of the base-band *H'*; but said band may 75 extend more or less below said disk, as desired, and thus the can may be set down over any causal projection which otherwise might break the glass bottom *s*, or cause damage to the can. The pasteboards *N N'* on their exterior surface 80 may have a lithograph or other ornamental finish, thus giving the can a very neat appearance. The bail *W* is attached to ears *w'*, soldered on either side of the can, over the spaces *r r'*, and thus the can may be conveniently held by the operator with one of said spaces toward his eye, in order that he may 85 observe the state of the oil in the can.

I claim—

1. An oil-can which comprises in combination a body portion, *A*, a metal cap, *B*, having apertures *g* located near the back of the neck *a* of the can, an air-space, *d*, pouring-spout *E*, and drip-spout *E'*, substantially as and for the purpose described. 90

2. The shouldered body portion of the oil-can, provided with a filling-neck, in combination with a paper and skeleton metal supporting, protecting, and absorbing jacket, comprising grooved shoulder and base bands, grooved vertical supports, and inclosing portions of suitable absorbent material, as paper, inserted into the grooves of the bands and vertical supports and confined thereby, substantially as and for the purpose described. 95

3. The combination, with the shouldered body portion *A* of the oil-can, provided with a filling-neck, of a supporting, protecting, and absorbing jacket comprising grooved shoulder and base bands, grooved vertical supports, inclosing portions of suitable absorbent material, as paper, inserted into the grooves of the bands and vertical supports, and a soft paper disk, *T*, fitted or set into the base-band, substantially as and for the purpose described. 100

4. An oil-can having a glass body, *A*, provided with a shoulder-band, *H*, base-band *H'*, longitudinal supports *m m'* and *m² m³*, and with a bail, *W*, hinged to an ear, *w'*, directly over a vacant space, *r r'*, between the supports *m* and *m'*, *m²* and *m³*, substantially as and for the purpose described. 105

5. The skeleton jacket comprising grooved shoulder and base bands, grooved vertical supports with inspection-spaces between each pair thereof, and inclosing portions of absorbent material, as paper, let into the grooves of 110

the bands and supports, in combination with an oil-can which comprises in its construction a projecting shoulder, *h*, below its upper contracted portion and filling-neck, substantially as and for the purpose described.

6. A paper sustaining and absorbing disk, *T*, let into the base-band of the supporting-jacket, in combination with the supporting-

jacket and oil-can having a suspending-shoulder, substantially as described.

In testimony whereof I affix my signature in presence of two witnesses.

GEORGE TRUBEL.
